(57) **CLAIM**

The ornamental design for a staple cartridge as shown and described.

DESCRIPTION

FIG. 1 is a front elevational view of the staple cartridge, showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a perspective view thereof.

The broken lines in the drawings depict portions of the staple cartridge that form no part of the claimed design.

1 Claim, 4 Drawing Sheets
